ABSTRACT

A liquid ejecting apparatus includes a common liquid chamber communicating with nozzles, a filter partitioning the common liquid chamber into an upstream chamber and a downstream chamber, an inlet and an outlet for the upstream chamber, a liquid storage section, a supply flow path, and a recovery flow path. A beam portion is provided inside the downstream chamber. A pressurization discharge operation for discharging the liquid from the nozzles by pressurizing the supply flow path and a circulation operation for circulating the liquid in a circulation path including the liquid storage section, the supply flow path, the common liquid chamber, and the recovery flow path, are performed. In a process of filling the circulation path with the liquid, the circulation operation is performed after the pressurization discharge operation is performed.

LIQUID EJECTING APPARATUS AND FILLING METHOD

The present application is based on, and claims priority from JP Application Serial Number 2022-123747, filed Aug. 3, 2022, the disclosure of which is hereby incorporated by reference herein in its entirety.

BACKGROUND

1. Technical Field

The present disclosure relates to a liquid ejecting apparatus and a filling method.

2. Related Art

In the related art, a liquid ejecting apparatus for ejecting a liquid such as an ink from a plurality of nozzles is known. For example, JP-A-2017-217612 discloses a liquid ejecting apparatus including a liquid storage section capable of storing a liquid, a common liquid chamber communicating with a plurality of nozzles, a supply flow path for supplying the liquid from the liquid storage section to the common liquid chamber, and a recovery flow path for recovering the liquid from the common liquid chamber to the liquid storage section. The common liquid chamber of the liquid ejecting apparatus disclosed in JP-A-2017-217612 is partitioned into an upstream chamber and a downstream chamber by a filter. The upstream chamber is provided with an inlet for communicating with the recovery flow path and introducing the liquid into the upstream chamber, and an outlet for communicating with the recovery flow path and causing the liquid to flow out.

In addition, JP-A-2021-187003 discloses a liquid ejecting apparatus including a liquid storage section, a liquid ejecting head having a plurality of nozzles, a supply flow path for supplying a liquid from the liquid storage section to the liquid ejecting head, and a recovery flow path for recovering the liquid from the liquid ejecting head, in which the liquid is circulated between the liquid storage section and the liquid ejecting head. The liquid ejecting apparatus disclosed in JP-A-2021-187003 has an on-off valve capable of opening and closing the recovery flow path. Furthermore, in JP-A-2021-187003, in a filling process of filling the supply flow path, the recovery flow path, and the liquid ejecting head with the liquid, a circulation operation is performed to circulate the liquid in a state where the recovery flow path is opened by the on-off valve. Thereafter, a pressurization discharge operation is performed to discharge the liquid from the liquid ejecting head by causing the on-off valve to close the recovery flow path.

In the liquid ejecting head disclosed in JP-A-2017-217612, it is conceivable that a beam portion extending in a direction intersecting with a direction in which the liquid flows from an inlet to a discharge port inside the common liquid chamber is provided in a flow path member forming the downstream chamber. In a case where the liquid ejecting head disclosed in JP-A-2017-217612 has the beam portion, when the filling process disclosed in JP-A-2021-187003 is performed, in some cases, air bubbles may stay between the filter and the beam portion due to the circulation operation.

SUMMARY

According to a preferred aspect of the present disclosure, there is provided a liquid ejecting apparatus including a

plurality of nozzles that eject a liquid in an ejection direction, a common liquid chamber that communicates with the plurality of nozzles and extends in a first direction orthogonal to the ejection direction, a filter that partitions the common liquid chamber into an upstream chamber and a downstream chamber, an inlet for introducing the liquid into the upstream chamber, an outlet for causing the liquid to flow out from the upstream chamber, a liquid storage section configured to store the liquid, a supply flow path that causes the inlet to communicate with the liquid storage section, and a recovery flow path that causes the outlet to communicate with the liquid storage section. A beam portion that couples a pair of inner walls for defining the downstream chamber is provided inside the downstream chamber. The pair of inner walls are separated in a direction intersecting with the first direction when viewed in the ejection direction. A pressurization discharge operation for discharging the liquid from the plurality of nozzles by pressurizing the supply flow path and a circulation operation for circulating the liquid in a circulation path including the liquid storage section, the supply flow path, the common liquid chamber, and the recovery flow path, in order of the liquid storage section, the supply flow path, the common liquid chamber, the recovery flow path, and the liquid storage section are performed. In a filling process of filling the circulation path with the liquid, the circulation operation is performed after the pressurization discharge operation is performed.

According to another preferred aspect of the present disclosure, there is provided a filling method for a liquid ejecting apparatus including a plurality of nozzles that eject a liquid in an ejection direction, a common liquid chamber that communicates with the plurality of nozzles and extends in a first direction orthogonal to the ejection direction, a filter that partitions the common liquid chamber into an upstream chamber and a downstream chamber, an inlet for introducing the liquid into the upstream chamber, an outlet for causing the liquid to flow out from the upstream chamber, a liquid storage section configured to store the liquid, a supply flow path that causes the inlet to communicate with the liquid storage section, and a recovery flow path that causes the outlet to communicate with the liquid storage section. A beam portion that couples a pair of inner walls for defining the downstream chamber is provided inside the downstream chamber, the pair of inner walls are separated in a direction intersecting with the first direction when viewed in the ejection direction, a pressurization discharge operation for discharging the liquid from the plurality of nozzles by pressurizing the supply flow path and a circulation operation for circulating the liquid in a circulation path including the liquid storage section, the supply flow path, the common liquid chamber, and the recovery flow path, in order of the liquid storage section, the supply flow path, the common liquid chamber, the recovery flow path, and the liquid storage section are performed. The filling method includes performing a filling process of filling the circulation path with the liquid, in which the circulation operation is performed after the pressurization discharge operation is performed.

BRIEF DESCRIPTION OF THE DRAWINGS

FIG. 1 is a schematic view illustrating an example of a liquid ejecting apparatus according to a first embodiment.

FIG. 2 is a view for describing a circulation mechanism and an on-off valve.

FIG. 3 is a perspective view of a liquid ejecting head and a support body according to the first embodiment.

FIG. 4 is an exploded perspective view of the liquid ejecting head according to the first embodiment.

FIG. 5 is an exploded perspective view of a head chip.

FIG. 6 is a cross-sectional view taken along line VI-VI in FIG. 5.

FIG. 7 is a cross-sectional view taken along line VII-VII in FIG. 5.

FIG. 8 is a view illustrating a flow of an ink inside a common liquid chamber while a circulation operation is performed in a state where a circulation path is not filled with the ink.

FIG. 9 is a view illustrating a flow of the ink inside the common liquid chamber while a pressurization discharge operation is performed after the circulation operation.

FIG. 10 is a flowchart illustrating a filling process of the present embodiment.

FIG. 11 is a view illustrating a flow of the ink inside the common liquid chamber in Step S2.

FIG. 12 is a view illustrating a flow of the ink inside the common liquid chamber in Step S6.

FIG. 13 is a view illustrating a flow of the ink inside the common liquid chamber while the pressurization discharge operation is performed in a liquid ejecting apparatus according to a first modification example.

FIG. 14 is a view illustrating a flow of the ink inside the common liquid chamber while the circulation operation performed after the pressurization discharge operation is performed in a liquid ejecting apparatus according to a second modification example.

FIG. 15 is a view illustrating a flow of the ink inside the common liquid chamber while the circulation operation performed after the pressurization discharge operation is performed in a liquid ejecting apparatus according to a third modification example.

FIG. 16 is a cross-sectional view taken along line XVI-XVI in FIG. 15.

FIG. 17 is a view for describing a head chip in a fourth modification example.

FIG. 18 is a view for describing the head chip in the fourth modification example.

FIG. 19 is a view for describing a flow path of a liquid ejecting apparatus in a fifth modification example.

FIG. 20 is a view for describing a flow path of a liquid ejecting apparatus according to a sixth modification example.

FIG. 21 is a view for describing a liquid ejecting apparatus according to a seventh modification example.

FIG. 22 is a view for describing a liquid ejecting apparatus according to an eighth modification example.

DESCRIPTION OF EMBODIMENTS

1. First Embodiment

Hereinafter, an embodiment for carrying out the present disclosure will be described with reference to the drawings. However, in each drawing, a dimension and a scale of each portion are appropriately different from actual ones. In addition, although the embodiment described below is a preferred specific example of the present disclosure, and thus, various technically preferable limitations are imposed. However, the scope of the present disclosure is not limited to these forms unless there is a description to such an effect that the present disclosure is particularly limited in the following description.

For the sake of convenience, the following description will be made by appropriately using an X-axis, a Y-axis, and

a Z-axis which intersect with each other. In addition, in the following description, one direction along the X-axis is an X1-direction, and a direction opposite to the X1-direction is an X2-direction. Similarly, mutually opposite directions along the Y-axis are a Y1-direction and a Y2-direction. In addition, mutually opposite directions along the Z-axis are a Z1-direction and a Z2-direction. In addition, viewing in a Z-axis direction may be simply referred to as a "plan view" in some cases. The Z2-direction is an example of an "ejection direction". The Y1-direction or the Y2-direction is an example of a "first direction". The X1-direction or the X2-direction is an example of a "third direction".

Here, typically, the Z-axis is a vertical axis, and in a first embodiment, the Z2-direction coincides with a gravity direction GV. In addition, the X-axis, the Y-axis, and the Z-axis are orthogonal to each other.

1-1. Schematic Configuration of Liquid Ejecting Apparatus

FIG. 1 is a schematic view illustrating an example of a liquid ejecting apparatus 100 according to the first embodiment. The liquid ejecting apparatus 100 is an ink jet printing apparatus that ejects an ink which is an example of a "liquid" onto a medium PP as a droplet. For example, the liquid ejecting apparatus 100 has a substantially box shape, and is mounted on a mounting surface orthogonal to the gravity direction GV. The medium PP is typically a printing paper. The medium PP is not limited to the printing paper, and for example, may be a printing target formed of any material such as a resin film or a fabric.

As illustrated in FIG. 1, the liquid ejecting apparatus 100 includes a main tank 10, a pump 12, a circulation mechanism 15, an on-off valve 16, a control module 20, a transport mechanism 30, a moving mechanism 40, and a liquid ejecting head 50.

The main tank 10 is a container for storing the ink. For example, specific aspects of the main tank 10 include a cartridge attachable to and detachable from the liquid ejecting apparatus 100, a bag-shaped ink pack formed of a flexible film, and a container such as an ink-refillable ink tank.

Although not illustrated, the main tank 10 has a plurality of containers that store mutually different types of the ink. 45 Although the ink stored in the plurality of containers are not particularly limited, for example, the ink includes a cyan ink, a magenta ink, a yellow ink, a black ink, a clear ink, a white ink, and a treatment liquid, and combinations of two or more types of these ink may be used. Each of the ink is not particularly limited in composition. For example, the ink may be a water-based ink in which a coloring material such as a dye and a pigment is dissolved in a water-based solvent, a solvent-based ink in which the coloring material is dissolved in an organic solvent, or an ultraviolet-curable ink.

As an example, the present embodiment adopts a configuration in which four mutually different types of the ink are used. For example, the four types of the ink are mutually different color ink such as the cyan ink, the magenta ink, the yellow ink, and the black ink.

The control module 20 controls an operation of each element of the liquid ejecting apparatus 100. For example, the control module 20 includes a processing circuit such as a CPU and an FPGA, and a memory circuit such as a semiconductor memory. The CPU is an abbreviation for central processing unit. The FPGA is an abbreviation for field programmable gate array. The control module 20 outputs a drive signal Com and a control signal SI toward the

liquid ejecting head 50. The drive signal Com is a signal including a drive pulse for driving a drive element of the liquid ejecting head 50. The control signal SI is a signal for designating whether or not to supply the drive signal Com to the drive element.

The transport mechanism 30 transports the medium PP in a transport direction DM which is the Y1-direction, under the control of the control module 20. The moving mechanism 40 causes the liquid ejecting head 50 to reciprocate in the X1-direction and the X2-direction under the control of the control module 20. In an example illustrated in FIG. 1, the moving mechanism 40 has a substantially box-shaped support body 41 called a carriage that accommodates the liquid ejecting head 50, and a transport belt 42 to which the support body 41 is fixed. In addition to the liquid ejecting head 50, the above-described main tank 10 may be mounted on the support body 41.

The liquid ejecting head 50 has a plurality of head chips 54 as will be described later and, under the control of the control module 20, the ink supplied from the main tank 10 is ejected from each of a plurality of nozzles N of each head chip 54 toward the medium PP in the Z2-direction which is the ejection direction. In the liquid ejecting apparatus 100, the ink is ejected in parallel when the medium PP is transported by the transport mechanism 30 and the liquid ejecting head 50 is caused to reciprocate by the moving mechanism 40. In this manner, a printing operation for forming a predetermined image on a surface of the medium PP is performed by using the ink.

The main tank 10 is coupled to the liquid ejecting head 50 via the circulation mechanism 15. The circulation mechanism 15 is a mechanism that supplies the ink to each of the plurality of liquid ejecting heads 50 under the control of the control module 20, and recovers the ink discharged from each of the plurality of liquid ejecting heads 50 to resupply the ink to the liquid ejecting head 50. The circulation mechanism 15 and the on-off valve 16 are provided for each of the mutually different types of the ink. The circulation mechanism 15 and the on-off valve 16 will be described with reference to FIG. 2.

1-2. Circulation Mechanism 15 and On-Off Valve 16

FIG. 2 is a view for describing the circulation mechanism 15 and the on-off valve 16. As illustrated in FIG. 2, the circulation mechanism 15 includes a sub tank 151 and a pump 159. In FIG. 2, any one type of the ink in the plurality of types of the ink will be described. FIG. 2 illustrates only two head chips 54 to which one type of the ink is supplied in the plurality of head chips 54 so that the drawing is not complicated. Furthermore, FIG. 2 illustrates the inside of only one head chip 54 in the two head chips 54 so that the drawing is not complicated.

The sub tank 151 is coupled to a supply flow path SF1 and a recovery flow path CF1, and stores the ink to be supplied to the plurality of liquid ejecting heads 50. The sub tank 151 stores the ink to be supplied to the liquid ejecting head 50, the ink recovered from the liquid ejecting head 50, and the ink supplemented from the main tank 10. The sub tank 151 is an example of a "liquid storage section".

The supply flow path SF1 causes an inlet Pin for introducing the ink into the head chip 54 to communicate with the sub tank 151. The supply flow path SF1 has an in-device supply flow path SJ1 and an in-head supply flow path SH1. The in-device supply flow path SJ1 is a flow path provided outside the liquid ejecting head 50, is coupled to the sub tank

151, and communicates with a head inlet Qin for introducing the ink into the liquid ejecting head 50. The in-head supply flow path SH1 is a flow path provided inside the liquid ejecting head 50, and supplies the ink to each of the plurality of head chips 54. The in-head supply flow path SH1 has a mainstream portion coupled to the in-device supply flow path SJ1 and a plurality of branch portions branched from the mainstream portion for each of the plurality of head chips 54. In the present embodiment, an example in which the main tank 10 is provided for each of four types of the ink and one type of the ink is supplied to two head chips 54 as illustrated in FIG. 2 will be described. Furthermore, it is assumed that two types of the ink can be supplied to one head chip 54. However, the liquid ejecting head 50 may supply any one type of the ink to three or more head chips 54 or may supply any one type of the ink to one head chip 54.

The recovery flow path CF1 causes an outlet Pout for causing the ink to flow out from the head chip 54 to communicate with the sub tank 151. The recovery flow path CF1 has an in-device recovery flow path CJ1 and an in-head recovery flow path CH1. The in-device recovery flow path CJ1 is a flow path provided outside the liquid ejecting head 50, is coupled to the sub tank 151, and communicates with a head outlet Qout for causing the ink to flow out from the liquid ejecting head 50. The in-head recovery flow path CH1 is a flow path provided inside the liquid ejecting head 50, and recovers the ink from each of the plurality of head chips 54. The in-head recovery flow path CH1 has a mainstream portion coupled to the in-device recovery flow path CJ1 and a plurality of branch portions for coupling the mainstream portion and each of the plurality of head chips 54.

The on-off valve 16 is provided in an intermediate portion of the in-device recovery flow path CJ1. The on-off valve 16 can close and open the in-device recovery flow path CJ1 under the control of the control module 20. In the following description, closing the in-device recovery flow path CJ1 by the on-off valve 16 may be referred to as "closing the on-off valve 16", and opening the in-device recovery flow path CJ1 by the on-off valve 16 may be referred to as "opening the on-off valve 16". A device other than the control module 20 may control the on-off valve 16. The on-off valve 16 may be any valve as long as the valve can be controlled from a device such as the control module 20, and for example, the valve may be a diaphragm valve, an electromagnetic valve, or an electric valve.

In the present embodiment, the on-off valve 16 is provided in the intermediate portion of the in-device recovery flow path CJ1. However, the on-off valve 16 may be provided in the intermediate portion of the mainstream portion of the in-head recovery flow path CH1. Alternatively, a plurality of the on-off valves 16 may be provided in the intermediate portion of each of the plurality of branch portions of the in-head recovery flow path CH1.

The pump 159 is provided in the intermediate portion of the in-device supply flow path SJ1. The pump 159 causes a first ink of the sub tank 151 to flow to the liquid ejecting head 50 under the control of the control module 20.

The head chip 54 is provided with a common liquid chamber R that communicates with the plurality of nozzles N. The common liquid chamber R is partitioned into an upstream chamber UR and a downstream chamber DR by a filter 54o. As illustrated in FIG. 2, the inlet Pin and the outlet Pout are provided in the upstream chamber UR. The plurality of nozzles N communicate with the downstream chamber DR. Internal elements of the head chip 54 will be described later with reference to FIGS. 5, 6, and 7.

As described above, the liquid ejecting apparatus **100** has a circulation path **KJ** having the sub tank **151**, the supply flow path **SF1**, the common liquid chamber **R**, and the recovery flow path **CF1**. Under an instruction of the control module **20**, the liquid ejecting apparatus **100** can perform a circulation operation for circulating the ink in the circulation path **KJ** in order of the sub tank **151**, the supply flow path **SF1**, the common liquid chamber **R**, the recovery flow path **CF1**, and the sub tank **151**.

In addition, when the ink is ejected from the nozzle **N**, the amount of the ink in the sub tank **151** is reduced. Therefore, the pump **12** appropriately supplements the ink of the sub tank **151** by supplying the ink from the main tank **10** to the sub tank **151** under the control of the control module **20**. For example, at a timing for supplementing the ink of the sub tank **151**, the ink is supplemented when a height of the ink of the sub tank **151** is lower than a predetermined height.

1-3. Attachment State of Liquid Ejecting Head **50**

FIG. 3 is a perspective view of the liquid ejecting head **50** and the support body **41** according to the first embodiment. As illustrated in FIG. 3, the liquid ejecting head **50** is supported by the support body **41**. The support body **41** is a member that supports the liquid ejecting head **50** and, as described above, the support body **41** is a substantially box-shaped carriage in the present embodiment. Here, the support body **41** is provided with an opening **41a** and a plurality of screw holes **41b**. In the present embodiment, the support body **41** has a substantially box shape with a plate-shaped bottom portion. For example, the bottom portion is provided with the opening **41a** and the plurality of screw holes **41b**. The liquid ejecting head **50** is fixed to the support body **41** by screwing using the plurality of screw holes **41b** in a state of being inserted into the opening **41a**. As described above, the liquid ejecting head **50** is attached to the support body **41**.

In an example illustrated in FIG. 3, one liquid ejecting head **50** is attached to the support body **41**. Two or more liquid ejecting heads **50** may be attached to the support body **41**. In this case, for example, the support body **41** is appropriately provided with the openings **41a** corresponding to the numbers or shapes of the liquid ejecting heads **50**.

1-4. Configuration of Liquid Ejecting Head

FIG. 4 is an exploded perspective view of the liquid ejecting head **50** according to the first embodiment. As illustrated in FIG. 4, the liquid ejecting head **50** has a flow path structure **51**, a substrate unit **52**, a holder **53**, four head chips **54_1** to **54_4**, a fixing plate **55**, and a cover **58**. These are disposed to be aligned in order of the cover **58**, the substrate unit **52**, the flow path structure **51**, the holder **53**, the four head chips **54**, and the fixing plate **55** in the Z2-direction. Hereinafter, each portion of the liquid ejecting head **50** will be described.

The flow path structure **51** is a structure internally provided with a flow path for supplying the ink stored in the above-described main tank **10** to the four head chips **54**. The flow path structure **51** has a flow path member **51a** and eight coupling pipes **51b**.

Although not illustrated, the flow path structure **51** is provided with four in-head supply flow paths **SH1** provided for each of four types of the ink and four in-head recovery flow paths **CH1** provided for each of four types of the ink. Each of the four in-head supply flow paths **SH1** has one head inlet **Qin** that receives the ink from the in-device supply flow

path **SJ1** and two discharge ports that discharge the ink toward the inlet **Pin** of the head chip **54**. Each of the four in-head recovery flow paths **CH1** has two inlets that receive the ink from the outlet **Pout** of the head chip **54** and one head outlet **Qout** that discharges the ink to the in-device recovery flow path **CJ1**. Each of the plurality of coupling pipes **51b** is either the head inlet **Qin** or the head outlet **Qout**, and is provided on a surface of the flow path member **51a** facing the Z1-direction. In contrast, each of the discharge port of each in-head supply flow path **SH1** and the inlet of each in-head recovery flow path **CH1** is provided on a surface of the flow path member **51a** facing the Z2-direction.

In addition, a plurality of wiring holes **51c** are provided in the flow path member **51a**. Each of the plurality of wiring holes **51c** is a hole through which a wiring substrate **54i** (to be described later) of the head chip **54** passes toward the substrate unit **52**. A side surface of the flow path member **51a** is provided with cutout portions at two locations in a circumferential direction. In addition, the flow path member **51a** is provided with a hole (not illustrated), and is fixed to the holder **53** by screwing using the hole.

Although not illustrated, the flow path member **51a** has a configuration of a stacked body in which a plurality of substrates are stacked in a direction along the Z-axis. Grooves and holes for forming the above-described in-head supply flow path **SH1** and in-head recovery flow path **CH1** are appropriately provided in each of the plurality of substrates. For example, these are joined to each other by using an adhesive, welding, or screwing.

Each of the eight coupling pipes **51b** is a pipe body protruding from the surface of the flow path member **51a** facing the Z1-direction. The eight coupling pipes **51b** correspond to the above-described four in-head supply flow paths **SH1** and the four in-head recovery flow paths **CH1**. The above-described eight coupling pipes **51b** are used by being coupled to the above-described sub tank **151** via a tube forming the in-device supply flow path **SJ1** and the in-device recovery flow path **CJ1**.

The substrate unit **52** is an assembly having a mounting component for electrically coupling the liquid ejecting head **50** to the control module **20**. The substrate unit **52** has a circuit substrate **52a**, a connector **52b**, and a support plate **52c**.

The circuit substrate **52a** is a printed wiring substrate such as a rigid wiring substrate having wiring for electrically coupling each head chip **54** and the connector **52b**. The circuit substrate **52a** is disposed on the flow path structure **51** via the support plate **52c**, and the connector **52b** is installed on the surface of the circuit substrate **52a** facing the Z1-direction.

The connector **52b** is a coupling component for electrically coupling the liquid ejecting head **50** and the control module **20**. The support plate **52c** is a plate-shaped member for attaching the circuit substrate **52a** to the flow path structure **51**. The circuit substrate **52a** is mounted on one surface of the support plate **52c**, and the circuit substrate **52a** is fixed to the support plate **52c** by screwing.

The holder **53** is a structure that accommodates and supports the four head chips **54**. The holder **53** has a substantially tray shape, and has a recess **53a**, a plurality of wiring holes **53c**, a plurality of recesses **53d**, a plurality of holes **53e**, a plurality of screw holes **53i**, and a plurality of screw holes **53k**. The recess **53a** is open in the Z1-direction, and is a space in which the above-described flow path member **51a** is disposed. Each of the plurality of wiring holes **53c** is a hole through which the wiring substrate **54i** of the head chip **54** passes toward the substrate unit **52**. Each

of the plurality of recesses **53d** is open in the Z2-direction, and is a space in which the head chip **54** is disposed. The plurality of holes **53e** are through holes for coupling each of the plurality of inlets Pin and outlet Pout which are provided in the plurality of head chips **54** (to be described later) and each of the discharge port of the in-head supply flow path SH1 and the inlet of the in-head recovery flow path CH1 which are formed in the flow path member **51a**. The plurality of screw holes **53i** are screw holes for screwing the holder **53** to the support body **41**. The plurality of screw holes **53k** are screw holes for screwing the cover **58** to the holder **53**.

Each head chip **54** ejects the ink. Each head chip **54** has the plurality of nozzles N ejecting a first ink and the plurality of nozzles N ejecting a second ink different in type from the first ink. Here, the first ink and the second ink are two of the above-described four types of the ink. For example, each of the head chip **54_1** and the head chip **54_2** uses two of the four types of the ink as the first ink and the second ink. Each of the head chip **54_3** and the head chip **54_4** uses the other remaining two of the four types of the ink. Each head chip **54** is provided with the wiring substrate **54i**. FIG. 4 illustrates a configuration of each head chip **54** in a simplified manner. The configuration of the head chip **54** will be described in detail with reference to FIG. 5 (to be described later).

The fixing plate **55** is a plate-shaped member to which the four head chips **54** and the holder **53** are fixed. Specifically, the fixing plate **55** is disposed in a state where the four head chips **54** are pinched between the holder **53** and the fixing plate **55**, and each head chip **54** and the holder **53** are fixed by using an adhesive. The fixing plate is provided with a plurality of opening portions **55a** exposing nozzle surfaces FN of the four head chips **54**. In an example illustrated in FIG. 4, the plurality of opening portions **55a** are individually provided for each head chip **54**. For example, the fixing plate **55** is made of a metal material such as stainless steel, titanium, and magnesium alloy.

The cover **58** is a box-shaped member that accommodates the substrate unit **52**. The cover **58** is provided with eight through holes **58a** and an opening portion **58b**. The eight through holes **58a** correspond to the eight coupling pipes **51b** of the flow path structure **51**, and the corresponding coupling pipes **51b** are inserted into the respective through holes **58a**. The above-described connector **52b** passes through the opening portion **58b** from the inside to the outside of the cover **58**.

1-5. Configuration of Head Chip

FIG. 5 is an exploded perspective view of the head chip **54**. FIG. 6 is a cross-sectional view taken along line VI-VI in FIG. 5. FIG. 7 is a cross-sectional view taken along line VII-VII in FIG. 5. However, in FIG. 7, the wiring substrate **54i** is omitted in illustration so that the drawing is not complicated. As illustrated in FIGS. 5 and 6, the head chip **54** has the plurality of nozzles N arranged in the direction along the Y-axis. The plurality of nozzles N are divided into a first nozzle row L1 and a second nozzle row L2 aligned apart from each other in the direction along the X-axis. Each of the first nozzle row L1 and the second nozzle row L2 is a set of the plurality of nozzles N linearly arranged in the direction along the Y-axis.

The head chips **54** are configured to be substantially symmetrical to each other in the direction along the X-axis. However, positions of the plurality of nozzles N of the first nozzle row L1 and the plurality of nozzles N of the second nozzle row L2 in the direction along the Y-axis may coincide

with or may be different from each other. As an example, FIG. 6 illustrates a configuration in which the positions of the plurality of nozzles N of the first nozzle row L1 and the plurality of nozzles N of the second nozzle row L2 coincide with each other in the direction along the Y-axis.

As illustrated in FIGS. 5 and 6, the head chip **54** has a flow path forming member **54a**, a pressure chamber substrate **54b**, a nozzle plate **54c**, a vibration absorber **54d**, a diaphragm **54e**, a plurality of piezoelectric elements **54f**, a protective substrate **54g**, the wiring substrate **54i**, a drive circuit **54j**, a frame body **54k**, a case **54n**, and a filter **54o**. However, in FIG. 5, the pressure chamber substrate **54b**, the diaphragm **54e**, the plurality of piezoelectric elements **54f**, the vibration absorber **54d**, the wiring substrate **54i**, the drive circuit **54j**, and the frame body **54k** are omitted in illustration so that the drawing is not complicated.

The flow path forming member **54a** and the pressure chamber substrate **54b** are stacked in the Z1-direction in this order to form a flow path for supplying the ink to the plurality of nozzles N. The filter **54o**, the pressure chamber substrate **54b**, the diaphragm **54e**, the plurality of piezoelectric elements **54f**, the protective substrate **54g**, the case **54n**, the wiring substrate **54i**, and the drive circuit **54j** are installed in a region located in the Z1-direction with respect to the flow path forming member **54a**. On the other hand, the nozzle plate **54c**, the vibration absorber **54d**, and the frame body **54k** are installed in a region located in the Z2-direction with respect to the flow path forming member **54a**. Each element of the head chip **54** is schematically a plate-shaped member elongated in the Y-direction, and the elements are joined to each other by using an adhesive, for example. Hereinafter, each element of the head chip **54** will be described in order.

The nozzle plate **54c** is a plate-shaped member provided with the plurality of nozzles N of each of the first nozzle row L1 and the plurality of nozzles N of the second nozzle row L2. Each of the plurality of nozzles N is a through hole through which the ink passes. Here, a surface of the nozzle plate **54c** facing the Z2-direction is the nozzle surface FN. That is, a normal direction of the nozzle surface FN is a direction of a normal vector of the nozzle surface FN, and is the Z2-direction which is the ejection direction.

The flow path forming member **54a** is provided with a downstream chamber DR, a plurality of coupling flow paths Ra, and a plurality of communication flow paths Na (to be described later), for each of the first nozzle row L1 and the second nozzle row L2. Here, the downstream chamber DR communicating with the plurality of nozzles N of the first nozzle row L1 will be referred to as a downstream chamber DR[L1]. The downstream chamber DR communicating with the plurality of nozzles N of the second nozzle row L2 will be referred to as a downstream chamber DR[L2].

The downstream chamber DR[L1] includes an opening DR1[L1] penetrating the flow path forming member **54a** in the Z-axis direction, an opening DR2[L1] penetrating the flow path forming member **54a** in the Z-axis direction, and a coupling flow path Xa[L1]. The opening DR1[L1] and the opening DR2[L1] are divided by a beam portion BR[L1] extending in the X-axis direction. Each of the opening DR1[L1] and the opening DR2[L1] extends in the Y-axis direction. Similarly, the downstream chamber DR[L2] includes an opening DR1[L2] penetrating the flow path forming member **54a** in the Z-axis direction, an opening DR2[L2] penetrating the flow path forming member **54a** in the Z-axis direction, and a coupling flow path Xa[L2]. The opening DR1[L2] and the opening DR2[L2] are divided by a beam portion BR[L2] extending in the X-axis direction.

Each of the opening DR1[L2] and the opening DR2[L2] extends in the Y-axis direction.

Here, when the openings DR1[L1] and DR1[L2] are not particularly distinguished, the openings will be simply referred to as an opening DR1. In addition, when the coupling flow path Xa[L1] and the coupling flow path Xa[L2] are not particularly distinguished, the coupling flow paths will be simply referred to as a coupling flow path Xa. Furthermore, when the openings DR2[L1] and DR2[L2] are not particularly distinguished, the openings will be simply referred to as an opening DR2. When the beam portion BR[L1] and the beam portion BR[L2] are not particularly distinguished, the beam portions will be simply referred to as a beam portion BR.

The beam portion BR extends along the X-axis, and couples inner walls wDR of the downstream chamber DR. The inner walls wDR are separated in the direction along the X-axis. However, an extending direction of the beam portion BR may be a direction intersecting with the Y-axis, and is not limited to the X-axis. The beam portion BR is a portion of the flow path forming member 54a. The beam portion BR is provided at a position substantially at the center in the direction along the Y-axis. Therefore, in FIG. 6, when a cross section taken along line VI-VI is viewed in the Y2-direction, the beam portion BR is originally visible. However, the opening DR1 is not illustrated to easily understand the opening DR1. Although one beam portion BR is provided corresponding to each of the first nozzle row L1 and the second nozzle row L2 in an example in FIG. 5, a plurality of the beam portions BR may be provided corresponding to the first nozzle row L1 and the second nozzle row L2. It can be said that the direction along the X-axis is a direction intersecting with the direction along the Y-axis. The direction along the X-axis is an example of "a direction intersecting with the first direction".

The coupling flow path Xa communicates with the plurality of coupling flow paths Ra in one end in the X-axis direction, and communicates with both the opening DR1 and the opening DR2 in the other end in the X-axis direction. That is, the ink passing through the openings DR1 and DR2 flows to the plurality of coupling flow paths Ra via the coupling flow path Xa. Each of the coupling flow path Ra and the communication flow path Na is a through hole formed for each nozzle N.

As illustrated in FIG. 6, a common liquid chamber R communicating with the plurality of nozzles N is provided for each of the first nozzle row L1 and the second nozzle row L2. The common liquid chamber R extends in a direction along the Y-axis orthogonal to the Z2-direction which is the ejection direction. In the following description, the common liquid chamber R communicating with the plurality of nozzles N of the first nozzle row L1 may be referred to as a common liquid chamber R[L1]. The common liquid chamber R communicating with the plurality of nozzles N of the second nozzle row L2 may be referred to as a common liquid chamber R[L2]. The common liquid chamber R stores the ink to be supplied to a plurality of pressure chambers CB. The common liquid chamber R is defined by a vibration absorber 54d, the flow path forming member 54a, the filter 54o, and the case 54n. The filter 54o partitions the common liquid chamber R into an upstream chamber UR and the downstream chamber DR. The flow path forming member 54a defines a portion of the downstream chamber DR.

The pressure chamber substrate 54b is a plate-shaped member provided with the plurality of pressure chambers CB for each of the first nozzle row L1 and the second nozzle row L2. The plurality of pressure chambers CB are arranged

in the direction along the Y-axis. Each pressure chamber CB is an elongated space formed for each nozzle N and extending in the direction along the X-axis in a plan view. As in the above-described nozzle plate 54c, each of the flow path forming member 54a and the pressure chamber substrate 54b is manufactured by processing a silicon single crystal substrate by using a semiconductor manufacturing technique, for example. However, other known methods and materials may be appropriately used for manufacturing each 10 of the flow path forming member 54a and the pressure chamber substrate 54b.

In addition, it is preferable that the flow path forming member 54a and the beam portion BR are formed of an integral silicon single crystal substrate. However, after each 15 of the flow path forming member 54a and the beam portion BR is separately manufactured, the beam portion BR may be welded to the flow path forming member 54a.

The pressure chamber CB is a space located between the flow path forming member 54a and the diaphragm 54e. The 20 plurality of pressure chambers CB are arranged in the direction along the Y-axis for each of the first nozzle row L1 and the second nozzle row L2. In addition, the pressure chamber CB communicates with each of the communication flow path Na and the coupling flow path Ra. Accordingly, 25 the pressure chamber CB communicates with the nozzle N via the communication flow path Na, and communicates with the downstream chamber DR via the coupling flow path Ra.

The diaphragm 54e is disposed on a surface of the 30 pressure chamber substrate 54b facing the Z1-direction. The diaphragm 54e is a plate-shaped member capable of vibrating elastically. For example, the diaphragm 54e has a first layer and a second layer, and the first layer and the second layer are stacked in the Z1-direction in this order. For 35 example, the first layer is an elastic film made of silicon oxide. For example, the elastic film is formed by thermally oxidizing one surface of a silicon single crystal substrate. For example, the second layer is an insulating film made of zirconium oxide. For example, the insulating film is formed 40 by forming a zirconium layer by sputtering and thermally oxidizing the layer. The diaphragm 54e is not limited to a configuration resulting from the stacking of the first layer and the second layer described above, and for example, may be configured to have a single layer, or may be configured to have three or more layers.

The plurality of piezoelectric elements 54f mutually corresponding to the nozzles N are disposed as drive elements for each of the first nozzle row L1 and the second nozzle row L2 on the surface of the diaphragm 54e facing the Z1-direction. Each piezoelectric element 54f is a passive element deformed by the supply of the drive signal Com. Each piezoelectric element 54f has an elongated shape extending in the direction along the X-axis in a plan view. The plurality of piezoelectric elements 54f are arranged in the direction 50 along the Y-axis to correspond to the plurality of pressure chambers CB. The piezoelectric element 54f overlaps the pressure chamber CB in a plan view.

Although not illustrated, each piezoelectric element 54f has a first electrode, a piezoelectric layer, and a second 60 electrode, and these are stacked in the Z1-direction in this order. One of the first electrode and the second electrode is an individual electrode disposed apart from each other for each piezoelectric element 54f, and the drive signal Com is applied to the one electrode. The other of the first electrode and the second electrode is a strip-shaped common electrode 65 extending in the direction along the Y-axis to be continuous over the plurality of piezoelectric elements 54f, and a

predetermined reference potential is supplied to the other electrode. For example, metal materials of these electrodes include metal materials such as platinum, aluminum, nickel, gold, and copper. Among these materials, one can be used alone, or two or more can be used in combination in an aspect of alloy or stacking. The piezoelectric layer is made of a piezoelectric material such as lead zirconate titanate, and for example, has a strip shape extending in the direction along the Y-axis to be continuous over the plurality of piezoelectric elements 54f. However, the piezoelectric layer may be integrated over the plurality of piezoelectric elements 54f. In this case, on the piezoelectric layer, a through hole penetrating the piezoelectric layer and extending in the direction along the X-axis is provided in a region corresponding to a gap between the pressure chambers CB adjacent to each other in a plan view. When the diaphragm 54e vibrates in conjunction with the deformation of the piezoelectric element 54f, a pressure inside the pressure chamber CB fluctuates to eject the ink from the nozzle N. As the drive element, a heating element for heating the ink inside the pressure chamber CB may be used instead of the piezoelectric element 54f.

The protective substrate 54g is a plate-shaped member installed on the surface of the diaphragm 54e facing the Z1-direction, protects the plurality of piezoelectric elements 54f, and reinforces mechanical strength of the diaphragm 54e. As illustrated in FIGS. 5 and 6, the protective substrate 54g is provided with an opening h1. The opening h1 is a hole through which the wiring substrate 54i passes. In addition, on the surface of the protective substrate 54g facing the Z2-direction, two recesses recessed in the Z1-direction are formed corresponding to each of the two first nozzle row L1 and second nozzle row L2. The plurality of piezoelectric elements 54f are accommodated between the recess of the protective substrate 54g and the diaphragm 54e. For example, the protective substrate 54g is configured to have a silicon single crystal substrate.

The filter 54o is a plate-shaped or sheet-shaped member stacked on the surface of the flow path forming member 54a facing the Z1-direction. The filter 54o captures foreign matters mixed in the ink while allowing passage of the ink.

The filter 54o is provided with a plurality of filter holes h23 through which the ink passes and an opening h21. The opening h21 is a through hole through which the pressure chamber substrate 54b passes. The plurality of filter holes h23 are provided inside a filter hole region FR. In the following description, the filter hole region FR provided with the filter hole h23 communicating with the downstream chamber DR[L1] may be referred to as a filter hole region FR[L1], and the filter hole region FR provided with the filter hole h23 communicating with the downstream chamber DR[L2] may be referred to as a filter hole region FR[L2]. The filter hole h23 provided in the filter hole region FR[L1] may be referred to as a filter hole h23[L1], and the filter hole h23 provided in the filter hole region FR[L2] may be referred to as a filter hole h23[L2]. The filter hole region FR is configured to have an electroformed filter. For example, a material forming the electroformed filter is Ni—Pd alloy. Alternatively, the material forming the electroformed filter may be stainless steel.

The case 54n is a member stacked on the surface of the filter 54o facing the Z1-direction. The case 54n defines the upstream chamber UR. The case 54n is provided with an opening h41, the upstream chamber UR communicating with the plurality of nozzles N of the first nozzle row L1, the upstream chamber UR communicating with the plurality of nozzles N of the second nozzle row L2, the inlet Pin

provided in each of the two upstream chambers UR, and the outlet Pout provided in each of the two upstream chambers UR. The opening h41 is a hole through which the wiring substrate 54i passes. In the following description, the upstream chamber UR included in the common liquid chamber R[L1] may be referred to as an upstream chamber UR[L1], and the upstream chamber UR included in the common liquid chamber R[L2] may be referred to as an upstream chamber UR[L2]. The upstream chamber UR is formed in such a manner that the case 54n is recessed in the Z1-direction from a surface SZ2 facing the Z2-direction.

The case 54n is made of a resin material such as a modified polyphenylene ether resin, a polyphenylene sulfide resin, and a polypropylene resin. Alternatively, the case 54n may be made of a metal material.

The vibration absorber 54d is also called a compliance substrate, is a flexible resin film forming a wall surface of the common liquid chamber R, and absorbs pressure fluctuations of the ink inside the common liquid chamber R. The vibration absorber 54d may be a flexible thin plate made of metal. A surface of the vibration absorber 54d facing the Z1-direction is joined to the flow path forming member 54a by using an adhesive. On the other hand, the frame body 54k is joined to the surface of the vibration absorber 54d facing the Z2-direction by using an adhesive. The frame body 54k is a frame-shaped member along an outer periphery of the vibration absorber 54d, and comes into contact with the above-described fixing plate 55. Here, for example, the frame body 54k is made of a metal material such as stainless steel, aluminum, titanium, and magnesium alloy.

The wiring substrate 54i is mounted on the surface of the diaphragm 54e facing the Z1-direction, and is a mounting component for electrically coupling the control module 20 and the head chip 54. For example, the wiring substrate 54i is a flexible wiring substrate such as COF, FPC, or FFC. The COF is an abbreviation for Chip On Film. The FPC is an abbreviation for Flexible Printed Circuit. The FFC is an abbreviation for Flexible Flat Cable. The drive circuit 54j for supplying a drive voltage to each piezoelectric element 54f is mounted on the wiring substrate 54i of the present embodiment. The drive circuit 54j is a circuit that switches whether or not to supply at least a portion of a waveform included in the drive signal Com as a drive pulse, based on the control signal SI.

1-6. Regarding Beam Portion BR

Rigidity of the flow path forming member 54a tends to be lower than rigidity of the case 54n. Specifically, the case 54n has an outer wall in the Z1-direction. Therefore, the rigidity can be maintained to some extent. On the other hand, the flow path forming member 54a has an elongated opening extending in the direction along the Y-axis. Therefore, the rigidity decreases. As the rigidity of the case 54n decreases, there is a possibility that the flow path forming member 54a may be deformed due to pressurization in a case of adhesive hardening, for example. Therefore, in the present embodiment, the beam portion BR is provided in the flow path forming member 54a. In this manner, it is possible to prevent a decrease in the rigidity of the flow path forming member 54a.

In accordance with the beam portion BR located at the center of the downstream chamber DR on the Y-axis, it is possible to further prevent a decrease in the rigidity of the flow path forming member 54a. Specifically, as illustrated in FIG. 7, the beam portion BR is included in a range YDR2 located at the center of a range YDR1, the range YDR2, and

a range YDR3 when the downstream chamber DR is equally divided into three by a plane parallel to an XZ-plane. Furthermore, although not illustrated in FIG. 7, it is preferable that the beam portion BR is included in a range located at the center when the downstream chamber DR is equally divided into five by a plane parallel to the XZ-plane.

It is preferable that the inlet Pin and the outlet Pout are respectively provided in both end portions of the common liquid chamber R in the direction along the Y-axis in the direction along the Y-axis. For example, the reason is as follows. When the inlet Pin and the outlet Pout are provided at the center of the common liquid chamber R in the direction along the Y-axis, the ink stagnates in both end portions of the common liquid chamber R in the direction along the Y-axis, and there is a high possibility that air bubbles may stay. Therefore, inevitably, as understood from FIGS. 5 and 7, the beam portion BR is located between the inlet Pin and the outlet Pout when viewed in the direction along the Z-axis. More specifically, positions of the beam portion BR, the inlet Pin, and the outlet Pout will be described by using a range YR1, a range YR2, and a range YR3 when the common liquid chamber R is equally divided into three by a plane parallel to the XZ-plane. The beam portion BR is included in the range YR2 located at the center of the range YR1, the range YR2, and the range YR3. The inlet Pin is included in the range YR3 located closest in the Y2-direction, in the range YR1, the range YR2, and the range YR3. The outlet Pout is included in the range YR1 located closest in the Y1-direction, in the range YR1, the range YR2, and the range YR3.

As illustrated in FIG. 7, a surface SB1 of the beam portion BR facing the case 54n is flush with a surface SB2 of the flow path forming member 54a facing the case 54n. The flush means that there is no step between two surfaces. Therefore, no gap is formed between the beam portion BR and the filter 54o in the direction along the Z-axis. The beam portion BR supports a portion of the filter 54o, specifically, a portion that overlaps the beam portion BR when viewed along the Z-axis.

1-7. Filling Process

As a method for filling the circulation path KJ with the ink in a state where the circulation path KJ is not filled with the ink, for example, it is conceivable to adopt the following aspect. After a circulation operation is performed, the on-off valve 16 is closed, and the supply flow path SF1 is pressurized by the pump 159. In this manner, a pressurization discharge operation for discharging the ink from the plurality of nozzles N is performed. However, the inventors have found the followings through experiments. In an aspect in which the common liquid chamber R has the filter 54o and the flow path forming member 54a has the beam portion BR, in the filling process in which the pressurization discharge operation is performed after the circulation operation is performed, the circulation operation causes the air bubbles to stay in a region pinched between the filter 54o and the beam portion BR or at a corner of the beam portion BR. Furthermore, the air bubbles combine with other air bubbles at a position where the air bubbles stay, and grow into large air bubbles. The region pinched between the two members means that one member of the two members is in contact with this region in one direction, and that the other member of the two members is in contact with this region in the other direction different from the one direction. The staying of the air bubbles in the region pinched between the filter 54o and

the beam portion BR or at the corner of the beam portion BR will be described with reference to FIGS. 8 and 9.

FIG. 8 is a view illustrating a flow of the ink inside the common liquid chamber R while the circulation operation is performed in a state where the circulation path KJ is not filled with the ink. However, in FIG. 8, and FIGS. 9, 11, and 12 (to be described later), the common liquid chamber R is illustrated as a rectangular shape to easily indicate the flow of the ink. Furthermore, in FIGS. 8, 9, 11, and 12, in order to intuitively indicate the flow of the ink, the flow of the ink is illustrated by increasing a size of an arrow indicating the flow of the ink as a flow rate of the ink increases. Furthermore, in FIGS. 8, 9, 11, and 12, a range filled with the ink is illustrated by shading with a broken line in a horizontal direction. Furthermore, in FIGS. 8, 9, 11, and 12, in order to indicate a positional relationship between the common liquid chamber R and the nozzle N, a contour of the nozzle N is illustrated by a broken line. Furthermore, FIGS. 8, 9, 11, and 12 illustrate a gravity direction GV. As described above, in the first embodiment, the gravity direction GV coincides with the Z2-direction. Therefore, a horizontal plane HF and the nozzle surface FN are parallel. Furthermore, in FIGS. 8, 9, 11, and 12, in order to facilitate understanding, in a state where the on-off valve 16 is open, the on-off valve 16 is illustrated as a white-outlined figure, and in a state where the on-off valve 16 is closed, the on-off valve 16 is illustrated as a black-painted figure. As illustrated in FIG. 8, the on-off valve 16 is open during the circulation operation.

As illustrated in FIG. 8, the ink introduced from the inlet Pin flows inside the upstream chamber UR, and is discharged from the outlet Pout. Furthermore, a portion of the ink introduced from the inlet Pin flows into the downstream chamber DR via the filter hole h23, and flows inside the downstream chamber DR. The flow rate of the ink inside the downstream chamber DR is lower than the flow rate of the ink inside the upstream chamber UR by the amount passing through the filter hole h23. Furthermore, as illustrated in FIG. 8, the ink flowing inside the downstream chamber DR collides with the beam portion BR, and branches in the Z2-direction and the Z1-direction.

The ink flows into the circulation path KJ in a state where the circulation path KJ is not filled with the ink. Therefore, the air filling the circulation path KJ becomes the air bubbles, and the air bubbles are generated in the common liquid chamber R. With regard to the pressure of the ink flowing through the common liquid chamber R while the circulation operation is performed, a strong negative pressure acts in the vicinity of the outlet Pout. Therefore, the air bubbles are less likely to stay, and the air bubbles in the vicinity of the outlet Pout are easily discharged from the outlet Pout. On the other hand, a negative pressure is less likely to act between the inlet Pin and the outlet Pout, compared to the vicinity of the outlet Pout. Therefore, the flow rate of the ink decreases. Furthermore, as described above, the flow rate of the ink inside the downstream chamber DR is lower than the flow rate of the ink inside the upstream chamber UR. Therefore, the air bubbles inside the downstream chamber DR are less affected by the flow of the ink in the circulation operation, and are relatively greatly affected by a buoyant force. Therefore, while moving in the Y1-direction, the air bubbles move in the Z1-direction which is an opposite direction of the gravity direction GV. As described above, the air bubbles located in the Y2-direction with respect to the beam portion BR inside the downstream chamber DR tend to grow after being gathered in the region pinched between the filter 54o and the beam portion BR or at the corner of the beam portion BR. FIG. 8

illustrates an air bubble BL located in the Y2-direction with respect to the beam portion BR and grown after being gathered in the region pinched between the filter 54o and the beam portion BR. It can be said that the position in the Y2-direction with respect to the beam portion BR is a position closer to the inlet Pin in the two directions along the Y-axis with respect to the beam portion BR.

FIG. 9 is a view illustrating a flow of the ink inside the common liquid chamber R while the pressurization discharge operation is performed after the circulation operation. In the pressurization discharge operation, the on-off valve 16 is closed, and the supply flow path SF1 is pressurized to discharge the ink from the plurality of nozzles N. Therefore, as illustrated in FIG. 9, the on-off valve 16 is closed during the pressurization discharge operation. In the pressurization discharge operation, the discharge port of the ink is only the nozzle N. Therefore, the ink is discharged from the nozzle N. As illustrated in FIG. 9, a droplet DP is discharged from each of the plurality of nozzles N. As illustrated in FIG. 9, the flow of the ink inside the upstream chamber UR reaches the downstream chamber DR via the filter hole h23 of the filter 54o. As illustrated in FIG. 9, a flowing direction of the ink inside the downstream chamber DR is a direction substantially parallel to the Z2-direction. A degree of the flow generated by the pressurization discharge operation cancels out the buoyant force acting on the air bubble BL, and the air bubble BL tends to stay as it is in the region pinched between the filter 54o and the beam portion BR or at the corner of the beam portion BR.

When a printing operation is performed while the air bubble BL stays, a large negative pressure acts on the common liquid chamber R in a case where a large amount of the ink is consumed for solid printing. In this manner, the air bubble BL is drawn into the nozzle N from the common liquid chamber R, thereby causing a possibility of poor ejection.

Therefore, in the filling process in the present embodiment, the liquid ejecting apparatus 100 performs the circulation operation after the pressurization discharge operation is performed.

1-8. Filling Process of First Embodiment

FIG. 10 is a flowchart illustrating the filling process of the present embodiment. In Step S2, the liquid ejecting apparatus 100 closes the on-off valve 16, and performs the pressurization discharge operation in a state where the circulation path KJ is not filled with the ink.

FIG. 11 is a view illustrating a flow of the ink inside the common liquid chamber R in Step S2. The ink flows into the circulation path KJ in a state where the circulation path KJ is not filled with the ink. Therefore, the air filling the circulation path KJ becomes the air bubbles, and the air bubbles are generated in the downstream chamber DR. However, in FIG. 11, the ink does not flow from the inlet Pin to the outlet Pout. Therefore, the air bubbles are not gathered in the region pinched between the filter 54o and the beam portion BR or at the corner of the beam portion BR. Therefore, the air bubbles generated in the downstream chamber DR are not combined with other air bubbles. Therefore, the air bubbles are likely to pass through the filter hole h23, and can move to the upstream chamber UR. In addition, the air bubbles inside the downstream chamber DR are relatively small. Therefore, the pressurization discharge operation causes the air bubbles to ride on the flow of the ink

directed toward the plurality of nozzles N from the inlet Pin. In this manner, the air bubbles are easily discharged from the nozzle N.

After Step S2 is completed, the liquid ejecting apparatus 100 opens the on-off valve 16 in Step S4, and performs the circulation operation in Step S6.

FIG. 12 is a view illustrating a flow of the ink inside the common liquid chamber R in Step S6. The circulation operation is performed in a state where the air bubbles are removed from the downstream chamber DR. Therefore, as illustrated in FIG. 12, the air bubbles do not stay in the region pinched between the filter 54o and the beam portion BR or at the corner of the beam portion BR. Furthermore, since the on-off valve 16 is opened, the recovery flow path CF1 is also filled with the ink.

After Step S6 is completed, the liquid ejecting apparatus 100 completes a series of processes illustrated in FIG. 10.

1-9. Summary of First Embodiment

As described above, the liquid ejecting apparatus 100 according to the first embodiment includes the plurality of nozzles N that eject the ink in the Z2-direction which is the ejection direction, the common liquid chamber R that communicates with the plurality of nozzles N and extends in the direction along the Y-axis orthogonal to the Z2-direction, the filter 54o that partitions the common liquid chamber R into the upstream chamber UR and the downstream chamber DR, the inlet Pin for introducing the ink into the upstream chamber UR, the outlet Pout for causing the ink to flow out from the upstream chamber UR, the sub tank 151 capable of storing the ink, the supply flow path SF1 that causes the inlet Pin to communicate with the sub tank 151, and the recovery flow path CF1 that causes the outlet Pout to communicate with the sub tank 151. A beam portion BR that couples the pair of inner walls wDR separated in the direction along the X-axis when viewed in the direction along the Z-axis and defining the downstream chamber DR is provided inside the downstream chamber DR. The pressurization discharge operation for discharging the ink from the plurality of nozzles N by pressurizing the supply flow path SF1 and the circulation operation for circulating the ink in the circulation path KJ including the sub tank 151, the supply flow path SF1, the common liquid chamber R, and the recovery flow path CF1, in order of the sub tank 151, the supply flow path SF1, the common liquid chamber R, the recovery flow path CF1, and the sub tank 151 are performed. In the filling process of filling the circulation path KJ with ink, the circulation operation is performed after the pressurization discharge operation is performed.

The pressurization discharge operation is performed before the circulation operation. In this manner, the ink does not flow from the inlet Pin to the outlet Pout before the pressurization discharge operation. Therefore, the air bubbles inside the downstream chamber DR are easily discharged. That is, the liquid ejecting apparatus 100 according to the first embodiment performs the circulation operation after discharging the air bubbles inside the downstream chamber DR. In this manner, compared to an aspect of performing the pressurization discharge operation after performing the circulation operation, it is possible to prevent the air bubbles from staying in the region pinched between the beam portion BR and the filter 54o by the circulation operation, and it is possible to reduce a possibility that the air bubbles may remain in the downstream chamber DR after the circulation operation.

In addition, the liquid ejecting apparatus 100 according to the first embodiment further includes the on-off valve 16 capable of opening and closing the recovery flow path CF1 according. The pressurization discharge operation is performed in a state where the recovery flow path CF1 is closed by the on-off valve 16, and the circulation operation is performed in a state where the recovery flow path CF1 is opened by the on-off valve 16.

In addition, the liquid ejecting apparatus 100 according to the first embodiment includes the flow path forming member 54a that defines a portion of the downstream chamber DR and supports the filter 54o. The beam portion BR is a portion of the flow path forming member 54a. A portion of the filter 54o is supported by the beam portion BR.

The liquid ejecting apparatus 100 according to the first embodiment can prevent the filter 54o from being bent in the Z2-direction, compared to an aspect having no beam portion BR. Therefore, the liquid ejecting apparatus 100 according to the first embodiment can stably support the filter 54o by preventing the bending of the filter 54o, and performs the pressurization discharge operation before the circulation operation. In this manner, it is possible to prevent the air bubbles from staying in the downstream chamber DR.

In addition, the beam portion BR is disposed between the inlet Pin and the outlet Pout when viewed in the direction along the Z-axis.

As described above, it is preferable that the inlet Pin and the outlet Pout are respectively provided in both end portions in the direction along the Y-axis of the common liquid chamber R in the direction along the Y-axis. Therefore, in the present embodiment, the beam portion BR is disposed between the inlet Pin and the outlet Pout when viewed in the direction along the Z-axis. In this manner, compared to an aspect in which the beam portion BR is not provided between the inlet Pin and the outlet Pout, it is possible to prevent the ink from stagnating in both end portions of the common liquid chamber R in the direction along the Y-axis. In a case where the beam portion BR is disposed between the inlet Pin and the outlet Pout when viewed in the direction along the Z-axis, when the circulation operation is performed before the pressurization discharge operation, the air bubbles stay in the region pinched between the filter 54o and the beam portion BR or at the corner of the beam portion BR. However, in the present embodiment, the pressurization discharge operation is performed before the circulation operation. In this manner, it is possible to prevent the air bubbles from staying in the downstream chamber DR.

2. Modification Examples

Each form described above as an example can be modified in various ways. Specific modification aspects will be described below as examples. Any two or more aspects selected from the following examples can be combined as appropriate within a mutually consistent range.

2-1. First Modification Example

In the first embodiment, the Z2-direction coincides with the gravity direction GV, but the present disclosure is not limited thereto.

FIG. 13 is a view illustrating a flow of the ink inside the common liquid chamber R while the pressurization discharge operation is performed in a liquid ejecting apparatus 100-A according to a first modification example. The liquid ejecting apparatus 100-A is different from the liquid ejecting apparatus 100 according to the first embodiment in that the

Y2-direction coincides with the gravity direction GV. Therefore, in the first modification example, the nozzle surface FN is inclined by 90 degrees with respect to the horizontal plane HF. In other words, in the common liquid chamber R according to the first modification example, the liquid ejecting apparatus 100-A can be used in a state where the common liquid chamber R according to the first embodiment is rotated counterclockwise around the X-axis as the central axis by 90 degrees when viewed in the X2-direction from the X1-direction.

In the aspect of performing the pressurization discharge operation after the circulation operation, the ink may be caused to flow from the inlet Pin to the outlet Pout by the circulation operation before the pressurization discharge operation. Therefore, there is a possibility that the air bubbles may stay in the region AR illustrated in FIG. 13. The region AR is a region located in the Y2-direction of the beam portion BR and pinched between the filter 54o and the beam portion BR. On the other hand, in the liquid ejecting apparatus 100-A according to the first modification example, the pressurization discharge operation is performed before the circulation operation. In this manner, the ink is not caused to flow from the inlet Pin to the outlet Pout by the circulation operation. Therefore, it is possible to prevent the air bubbles from staying in the region AR.

In addition, in the first modification example, an aspect has been described in which the liquid ejecting apparatus 100-A is used in a state where the common liquid chamber R is rotated counterclockwise around the X-axis as the central axis by 90 degrees when viewed in the X2-direction from the X1-direction. However, the aspect in which the liquid ejecting apparatus 100 is used is not limited to the first modification example. For example, even in an aspect in which the liquid ejecting apparatus 100 is used in a state where the common liquid chamber R is rotated counterclockwise around the X-axis as the central axis by an angle larger than zero degrees and smaller than 90 degrees when viewed in the X2-direction from the X1-direction, compared to the aspect of performing the pressurization discharge operation after the circulation operation is performed, it is possible to reduce a possibility that air bubbles may remain in the common liquid chamber R after the circulation operation.

2-2. Second Modification Example

In the first embodiment, the distances between the inlet Pin and the outlet Pout from the horizontal plane HF are the same, and in the first modification example, the distance from the horizontal plane HF to the inlet Pin is shorter than the distance from the horizontal plane HF to the outlet Pout. However, the aspect of using the liquid ejecting apparatus 100 is not limited to the first embodiment and the first modification example. For example, even in an aspect in which the liquid ejecting apparatus 100 is used in a state where the distance from the horizontal plane HF to the inlet Pin is longer than the distance from the horizontal plane HF to the outlet Pout, compared to the aspect of performing the pressurization discharge operation after the circulation operation is performed, in some cases, it is possible to reduce the possibility that the air bubbles may remain in the common liquid chamber R after the circulation operation.

FIG. 14 is a view illustrating a flow of the ink inside the common liquid chamber R while the circulation operation is performed after the pressurization discharge operation is performed in a liquid ejecting apparatus 100-B according to a second modification example. The liquid ejecting appara-

tus 100-B is different from the liquid ejecting apparatus 100 according to the first embodiment in that a V1-direction orthogonal to the X-axis and obtained by rotating the Z2-direction counterclockwise by 15 degrees when viewed in the X2-direction from the X1-direction coincides with the gravity direction GV. FIG. 14 illustrates an aspect in which the liquid ejecting apparatus 100-B is used in a state where the common liquid chamber R is rotated clockwise around the X-axis as the central axis by 15 degrees when viewed in the X2-direction from the X1-direction.

In the second modification example, in the aspect of performing the pressurization discharge operation after the circulation operation is performed, in some cases, a force for moving the air bubbles in the Y1-direction by the circulation operation may be greater than a force for moving the air bubbles in the Y2-direction by the buoyant force. However, even in the aspect of using the liquid ejecting apparatus 100-B according to the second modification example, compared to the aspect of performing the pressurization discharge operation after the circulation operation is performed, it is possible to reduce the possibility that the air bubbles may remain in the common liquid chamber R after the circulation operation.

In addition, in the second modification example, an aspect has been described in which the liquid ejecting apparatus 100-B is used in a state where the common liquid chamber R is rotated clockwise around the X-axis as the central axis by 15 degrees when viewed in the X2-direction from the X1-direction. However, the aspect of using the liquid ejecting apparatus 100 is not limited to the second modification example. For example, in an aspect in which the liquid ejecting apparatus 100 is used in a state where the common liquid chamber R is rotated around the X-axis as the central axis by an angle larger than zero degrees and smaller than 15 degrees clockwise when viewed in the X2-direction from the X1-direction, compared to the aspect of performing the pressurization discharge operation after the circulation operation is performed, it is possible to reduce the possibility that the air bubbles may remain in the common liquid chamber R after the circulation operation.

2-3. Third Modification Example

In the first modification example and the second modification example, the aspect has been described in which the liquid ejecting apparatus 100 is used in a state where the common liquid chamber R is rotated around the X-axis as the central axis. However, the aspect of using the liquid ejecting apparatus 100 is not limited thereto. For example, even in an aspect in which the liquid ejecting apparatus 100 is used in a state where the common liquid chamber R is rotated around the Y-axis as the central axis, compared to the aspect of performing the pressurization discharge operation after the circulation operation is performed, in some cases, it is possible to reduce the possibility that the air bubbles may remain in the common liquid chamber R after the circulation operation.

FIG. 15 is a view illustrating a flow of the ink inside the common liquid chamber R while the circulation operation is performed after the pressurization discharge operation is performed in a liquid ejecting apparatus 100-C according to a third modification example. FIG. 16 is a cross-sectional view taken along line XVI-XVI in FIG. 15. However, in FIG. 15, the head chip 54 according to the third modification example is illustrated only in the X2-direction of the wiring substrate 54i, in a cross section parallel to the XZ-plane and cut along the plane passing through the beam portion BR.

The liquid ejecting apparatus 100-C is different from the liquid ejecting apparatus 100 according to the first embodiment in that the X1-direction coincides with the gravity direction GV. FIGS. 15 and 16 illustrate an aspect in which the liquid ejecting apparatus 100-C is used in a state where the common liquid chamber R is rotated clockwise around the Y-axis as the central axis by 90 degrees when viewed in the Y1-direction from the Y2-direction. In addition, in FIG. 16, the head chip 54 is illustrated in a simplified manner, and the nozzle plate 54c and the vibration absorber 54d are omitted in illustration. Furthermore, the vicinity of the downstream chamber DR[L1] is illustrated. Furthermore, in FIG. 16, in order to indicate a positional relationship between the downstream chamber DR[L1], the inlet Pin [L1], and the outlet Pout[L1], the inlet Pin[L1] and the outlet Pout[L1] are indicated by a one-dot chain line.

In the aspect of performing the pressurization discharge operation after the circulation operation, the ink may be caused to flow from the inlet Pin to the outlet Pout by the circulation operation before the pressurization discharge operation. Therefore, there is a possibility that the air bubbles may stay in a region AR-C illustrated in FIG. 16. The region AR-C is a region located in the Y2-direction with respect to the beam portion BR[L1] and pinched between the inner wall wDR of the opening DR1[L1] in the X2-direction and the beam portion BR[L1]. On the other hand, in the liquid ejecting apparatus 100-C according to the third modification example, the pressurization discharge operation is performed before the circulation operation. In this manner, the ink is not caused to flow from the inlet Pin to the outlet Pout by the circulation operation. Therefore, it is possible to prevent the air bubbles from staying in the region AR-C.

In addition, in the third modification example, an aspect has been described in which the liquid ejecting apparatus 100-C is used in a state where the common liquid chamber R is rotated clockwise around the Y-axis as the central axis by 90 degrees when viewed in the Y1-direction from the Y2-direction. However, the aspect of using the liquid ejecting apparatus 100 is not limited to the third modification example. For example, even in an aspect in which the liquid ejecting apparatus 100 is used in a state where the common liquid chamber R is rotated clockwise around the Y-axis as the central axis by an angle larger than zero degrees and smaller than 90 degrees when viewed in the Y1-direction from the Y2-direction, compared to the aspect of performing the pressurization discharge operation after the circulation operation is performed, it is possible to reduce the possibility that the air bubbles may remain in the common liquid chamber R after the circulation operation. Furthermore, even in an aspect in which the liquid ejecting apparatus 100 is used in a state where the common liquid chamber R is rotated counterclockwise around the Y-axis as the central axis by an angle larger than zero degrees and equal to or smaller than 90 degrees when viewed in the Y1-direction from the Y2-direction, compared to the aspect of performing the pressurization discharge operation after the circulation operation is performed, it is possible to reduce the possibility that the air bubbles may remain in the common liquid chamber R after the circulation operation.

2-4. Fourth Modification Example

In each of the above-described aspects, the filter 54o and the beam portion BR are disposed without a gap in the direction along the Z-axis, but may be disposed with a gap.

FIGS. 17 and 18 are views for describing a head chip 54-D in a fourth modification example. FIG. 17 illustrates a

cross section when the head chip **54-D** is cut along line VII-VII in FIG. 5. FIG. 18 illustrates only an element located in the X2-direction with respect to the wiring substrate **54i**, in the cross section when the head chip **54-D** is cut along line VII-VII in FIG. 5.

The head chip **54-D** is different from the head chip **54** in that a flow path forming member **54a-D** is provided instead of the flow path forming member **54a**. The flow path forming member **54a-D** is different from the flow path forming member **54a** in that a beam portion **BR-D** is provided instead of the beam portion **BR**. As illustrated in FIGS. 17 and 18, a surface **SB1-D** of the beam portion **BR-D** facing the case **54n** is located in the Z2-direction with respect to the surface **SB2** of the flow path forming member **54a** facing the case **54n**. Therefore, a gap **GP** is formed between the filter **54o** and the beam portion **BR-D** in the direction along the Z-axis.

As illustrated in FIGS. 17 and 18, a dimension **CZ** of the gap **GP** in the direction along the Z-axis is shorter than a distance **DZ** between the beam portion **BR-D** and a bottom surface of the downstream chamber **DR**. In addition, as illustrated in FIG. 18, the dimension **CZ** is shorter than a dimension **BX** of the beam portion **BR-D** in the direction along the X-axis. Furthermore, the dimension **CZ** is shorter than a dimension **BZ** of the beam portion **BR-D** in the direction along the Z-axis and a dimension **BY** of the beam portion **BR-D** in the direction along the Y-axis.

As described above, in the liquid ejecting apparatus **100** according to the fourth modification example, the filter **54o** and the beam portion **BR-D** are disposed with the gap **GP** in the direction along the Z-axis, and the dimension **CZ** of the gap **GP** in the direction along the Z-axis is shorter than the distance **DZ** between the beam portion **BR-D** and the bottom surface of the downstream chamber **DR**.

As the dimension **CZ** is lengthened, the distance from the filter **54o** in the direction along the Z-axis increases. Therefore, it is difficult to stably support the filter **54o**. However, in the liquid ejecting apparatus **100** according to the fourth modification example, the gap **GP** is formed so that the dimension **CZ** is shorter than the distance **DZ**. Therefore, the filter **54o** can be stably supported, compared to an aspect in which the dimension **CZ** is longer than the distance **DZ**. However, since the dimension **CZ** is shorter than the distance **DZ**, the air bubbles inside the downstream chamber **DR** are less likely to move from the inlet **Pin** to the outlet **Pout** after passing through the gap **GP**. However, the circulation operation is also performed after the pressurization discharge operation in the fourth modification example. Therefore, the air bubbles are prevented from staying and growing on the inlet **Pin** side of the beam portion **BR-D** without passing through the gap **GP**, and as in the first embodiment, it is possible to prevent the air bubbles from staying in the downstream chamber **DR**.

In addition, the dimension **CZ** is shorter than the dimension **BX** of the beam portion **BR-D** in the direction along the X-axis.

In the same manner as described above, the liquid ejecting apparatus **100** according to the fourth modification example can stably support the filter **54o**, compared to an aspect in which the dimension **CZ** is longer than the dimension **BX**. In addition, since the circulation operation is performed after the pressurization discharge operation, it is possible to prevent the air bubbles from staying in the downstream chamber **DR**.

In addition, the dimension **CZ** is shorter than the dimension **BZ** of the beam portion **BR-D** in the direction along the

Z-axis and the dimension **BY** of the beam portion **BR-D** in the direction along the Y-axis.

When each of the dimension **BZ** and the dimension **BY** is shortened, rigidity of the beam portion **BR-D** decreases, and thus, rigidity of the flow path forming member **54a-D** decreases. Therefore, in the liquid ejecting apparatus **100** according to the fourth modification example, it is possible to prevent a decrease in the rigidity of the flow path forming member **54a-D**, compared to an aspect in which the dimension **CZ** is longer than the dimension **BZ** and an aspect in which the dimension **CZ** is longer than the dimension **BY**. In addition, since the circulation operation is performed after the pressurization discharge operation, it is possible to prevent the air bubbles from staying in the downstream chamber **DR**.

2-5. Fifth Modification Example

The liquid ejecting apparatus **100** in each of the above-described aspects may further have a bypass flow path **BP** that couples the supply flow path **SF1** and the recovery flow path **CF1**.

FIG. 19 is a view for describing a flow path of a liquid ejecting apparatus **100-E** in a fifth modification example. The liquid ejecting apparatus **100-E** is different from the liquid ejecting apparatus **100** according to the first embodiment in that a bypass flow path **BP** for coupling the supply flow path **SF1** and the recovery flow path **CF1** is provided. In an example in FIG. 19, the bypass flow path **BP** is a flow path provided outside the liquid ejecting head **50**. One end **Rin** of the bypass flow path **BP** is provided between the pump **159** of the in-device supply flow path **SJ1** and the head inlet **Qin** in the supply flow path **SF1**. However, the bypass flow path **BP** may be provided inside the liquid ejecting head **50**, and may be further provided for each head chip **54**.

The other end **Rout** of the bypass flow path **BP** is provided between the on-off valve **16** of the in-device recovery flow path **CJ1** and the head outlet **Qout** in the recovery flow path **CF1**.

FIG. 19 illustrates a flow of the ink while the pressurization discharge operation is performed. In the pressurization discharge operation, the on-off valve **16** is closed. As illustrated in FIG. 19, a flow **FR1** and a flow **FR2** are generated by the pressurization of the pump **159**. The flow **FR1** is a flow in which the ink flows in order of the supply flow path **SF1**, the common liquid chamber **R**, and the nozzle **N**. The flow **FR2** is a flow in which the ink flows in order of the bypass flow path **BP**, the flow path from the other end **Rout** of the recovery flow path **CF1** to the outlet **Pout**, the common liquid chamber **R**, and the nozzle **N**. The flow path from the other end **Rout** to the outlet **Pout** of the recovery flow path **CF1** is an example of “a portion of the recovery flow path”.

As described above, in the liquid ejecting apparatus **100-E** according to the fifth modification example, in the pressurization discharge operation, the supply flow path **SF1** and the recovery flow path **CF1** are pressurized to generate the flow **FR1** in which the ink flows in order of the supply flow path **SF1**, the common liquid chamber **R**, and the plurality of nozzles **N**, and the flow **FR2** in which the ink flows in order of a portion of the recovery flow path **CF1**, the common liquid chamber **R**, and the plurality of nozzles **N**.

In the liquid ejecting apparatus **100-E** according to the fifth modification example, as in the first embodiment, compared to an aspect in which the air bubbles inside the common liquid chamber **R** are discharged only through the flow **FR1** in the pressurization discharge operation, it is

possible to reduce the amount of the air bubbles remaining inside the common liquid chamber R. Specifically, in the first embodiment, the flow paths are pressurized only from the inlet Pin, and the flow paths are not pressurized from the outlet Pout. However, in the fifth modification example, the flow paths are pressurized from the inlet Pin and the outlet Pout. Therefore, the liquid ejecting apparatus 100-E according to the fifth modification example can increase the pressure applied to the nozzle N closer to the outlet Pout than the inlet Pin in the plurality of nozzles N, compared to the liquid ejecting apparatus 100 according to the first embodiment. Therefore, the air bubbles can be more discharged from the nozzle N.

2-6. Sixth Modification Example

The liquid ejecting apparatus 100 in each of the above-described aspects except for the fifth modification example may have a pump in the in-device recovery flow path CJ1 instead of the on-off valve 16.

FIG. 20 is a view for describing a flow path of a liquid ejecting apparatus 100-F according to a sixth modification example. The liquid ejecting apparatus 100-F is different from the liquid ejecting apparatus 100 according to the first embodiment in that the pump 158 is provided instead of the on-off valve 16. The pump 158 can apply a positive pressure and a negative pressure to the outlet Pout.

In an example in FIG. 20, the pump 158 is included in the circulation mechanism 15. In the circulation operation, the pump 158 generates the negative pressure with respect to the outlet Pout. In this manner, the ink can be circulated faster, compared to the liquid ejecting apparatus 100 according to the first embodiment.

Furthermore, in the pressurization discharge operation performed before the circulation operation, the supply flow path SF1 is pressurized by the pump 159, and the recovery flow path CF1 is pressurized by the pump 158, thereby generating the flow FR1 in which the ink flows in order of the supply flow path SF1, the common liquid chamber R, and the plurality of nozzles N, and a flow FR2-F in which the ink flows in order of the recovery flow path CF1, the common liquid chamber R, and the plurality of nozzles N.

As described above, in the liquid ejecting apparatus 100-F according to the sixth modification example, as in the liquid ejecting apparatus 100-E according to the fifth modification example, compared to an aspect in which the air bubbles inside the common liquid chamber R are discharged only through the flow FR1 in the pressurization discharge operation, it is possible to reduce the amount of the air bubbles remaining inside the common liquid chamber R.

2-7. Seventh Modification Example

The common liquid chamber R according to each of the above-described aspects is provided with one inlet Pin and one outlet Pout, but the present disclosure is not limited thereto.

FIG. 21 is a view for describing a liquid ejecting apparatus 100-G according to a seventh modification example. The liquid ejecting apparatus 100-G is different from the liquid ejecting apparatus 100 according to the first embodiment in that a case 54n-G is provided instead of the case 54n and the head chip 54 having a flow path forming member 54a-G is provided instead of the flow path forming member 54a. A common liquid chamber R-G is formed by the case 54n-G and the flow path forming member 54a-G. The common liquid chamber R-G is different from the common

liquid chamber R in that an upstream chamber UR-G is provided instead of the upstream chamber UR and a downstream chamber DR-G is provided instead of the downstream chamber DR.

The case 54n-G is different from the case 54n in that the case 54n-G is provided with an inlet Pin-G1 and an inlet Pin-G2 instead of the inlet Pin and is provided with an outlet Pout-G instead of the outlet Pout. Hereinafter, in some cases, the inlet Pin-G1 and the inlet Pin-G2 may be collectively referred to as an inlet Pin-G. As illustrated in FIG. 21, the inlet Pin-G1 is provided in an end portion of the upstream chamber UR-G in the Y1-direction. The inlet Pin-G2 is provided in an end portion of the upstream chamber UR-G in the Y2-direction. The outlet Pout-G is provided between the inlet Pin-G1 and the inlet Pin-G2, and more specifically, is provided in the vicinity of the center of the upstream chamber UR-G.

As illustrated in FIG. 21, the inlet Pin-G1 is coupled to the in-head supply flow path SH1-G1, and the inlet Pin-G2 is coupled to the in-head supply flow path SH1-G2. The in-head supply flow path SH1-G1 and the in-head supply flow path SH1-G2 are flow paths inside the liquid ejecting head 50 according to the seventh modification example, and are flow paths provided instead of the in-head supply flow path SH1. Each of the in-head supply flow path SH1-G1 and the in-head supply flow path SH1-G2 is coupled to a mainstream portion coupled to the head inlet Qin. The outlet Pout-G is coupled to the in-head recovery flow path CH1.

The flow path forming member 54a-G is different from the flow path forming member 54a in that the flow path forming member 54a-G is provided with a beam portion BR-G1 and is provided with a beam portion BR-G2 instead of the beam portion BR. As understood from FIG. 21, the beam portion BR-G1 is provided between the inlet Pin-G1 and the outlet Pout-G when viewed in the direction along the Z-axis. The beam portion BR-G2 is provided between the inlet Pin-G2 and the outlet Pout-G when viewed in the direction along the Z-axis.

FIG. 21 illustrates a flow of the ink in the circulation operation after the pressurization discharge operation in the seventh modification example. As illustrated in FIG. 21, the ink supplied from the inlets Pin-G respectively provided in both end portions of the upstream chamber UR-G in the direction along the Y-axis is discharged from the outlet Pout-G provided at the center of the upstream chamber UR-G. Furthermore, in the ink supplied from the inlet Pin-G, the ink flowing into the downstream chamber DR-G via the filter 54o is also discharged from the outlet Pout-G at the center of the downstream chamber DR-G via the upstream chamber UR-G.

In the aspect of performing the pressurization discharge operation after the circulation operation, the ink may be caused to flow from the inlet Pin-G to the outlet Pout-G by the circulation operation before the pressurization discharge operation. Therefore, there is a possibility that the air bubbles may stay in a region AR-G1 and a region AR-G2 illustrated in FIG. 21. The region AR-G1 is a region located in the Y1-direction with respect to the beam portion BR-G1 and pinched between the beam portion BR-G1 and the filter 54o. The region AR-G2 is a region located in the Y2-direction with respect to the beam portion BR-G2 and pinched between the beam portion BR-G2 and the filter 54o. On the other hand, the liquid ejecting apparatus 100-G according to the seventh modification example performs the pressurization discharge operation before the circulation operation. In this manner, the ink is not caused to flow from the inlet Pin-G1 and the inlet Pin-G2 to the outlet Pout-G by the

circulation operation. Therefore, it is possible to prevent the air bubbles from staying in the region AR-G1 and the region AR-G2.

2-8. Eighth Modification Example

In the seventh modification example, two inlets Pin are provided for one common liquid chamber R, and one outlet Pout is provided for one common liquid chamber R, but the present disclosure is not limited thereto.

FIG. 22 is a view for describing a liquid ejecting apparatus 100-H according to an eighth modification example. The liquid ejecting apparatus 100-H is different from the liquid ejecting apparatus 100-G in that one inlet Pin-H is provided for a common liquid chamber R-H according to the eighth modification example, and an outlet Pout-H1 and an outlet Pout-H2 are provided. Hereinafter, in some cases, the outlet Pout-H1 and the outlet Pout-H2 may be collectively referred to as an outlet Pout-H. The shape of the head chip 54 according to the eighth modification example is the same as the shape of the head chip 54 according to the seventh modification example. In the eighth modification example, the common liquid chamber R-H is formed by the case 54n-G and the flow path forming member 54a-G. The common liquid chamber R-H is different from the common liquid chamber R-G in that an upstream chamber UR-H is provided instead of the upstream chamber UR-G.

In the upstream chamber UR-H, an opening that functions as the inlet Pin-G1 functions as an outlet Pout-H1 in the upstream chamber UR-G, an opening that functions as the inlet Pin-G2 functions as an outlet Pout-H2 in the upstream chamber UR-G, and an opening that functions as the outlet Pout-G functions as an inlet Pin-H in the upstream chamber UR-G.

As illustrated in FIG. 22, the outlet Pout-H1 is coupled to an in-head recovery flow path CH1-H1, and the outlet Pout-H2 is coupled to an in-head recovery flow path CH1-H2. The in-head recovery flow path CH1-H1 and the in-head recovery flow path CH1-H2 are flow paths inside the liquid ejecting head 50 according to the eighth modification example, and are flow paths provided instead of the in-head recovery flow path CH1. Each of the in-head recovery flow path CH1-H1 and the in-head recovery flow path CH1-H2 is coupled to a mainstream portion coupled to the head outlet Qout. The inlet Pin-H is coupled to the in-head supply flow path SH1.

FIG. 22 illustrates a flow of the ink in the circulation operation after the pressurization discharge operation in the eighth modification example. As illustrated in FIG. 22, the ink supplied from the inlet Pin-H provided at the center of the upstream chamber UR-G in the direction along the Y-axis is discharged from the outlet Pout-H provided in each of both end portions of the upstream chamber UR-H in the direction along the Y-axis. Furthermore, in the ink supplied from the inlet Pin-H, the ink flowing into the downstream chamber DR-G via the filter 54o is also discharged from the outlet Pout-H in each of both end portions of the downstream chamber DR-G via the upstream chamber UR-H.

In the aspect of performing the pressurization discharge operation after the circulation operation, the ink may be caused to flow from the inlet Pin-H to each of the outlets Pout-H by the circulation operation before the pressurization discharge operation. Therefore, there is a possibility that the air bubbles may stay in a region AR-H1 and a region AR-H2 illustrated in FIG. 22. The region AR-H1 is a region located in the Y2-direction with respect to the beam portion BR-G1 and the filter

54o. The region AR-H2 is a region located in the Y1-direction with respect to the beam portion BR-G2 and pinched between the beam portion BR-G2 and the filter 54o. On the other hand, the liquid ejecting apparatus 100-H according to the eighth modification example performs the pressurization discharge operation before the circulation operation. In this manner, the ink is not caused to flow from the inlet Pin-H to the outlet Pout-H1 or the outlet Pout-H2 by the circulation operation. Therefore, it is possible to prevent the air bubbles from staying in the region AR-H1 and the region AR-H2.

2-9. Ninth Modification Example

In each of the above-described aspects, the serial type liquid ejecting apparatus 100 in which the liquid ejecting head 50 reciprocates in the direction along the X-axis has been described as an example, but the present disclosure is not limited to this aspect. The liquid ejecting apparatus may be a line-type liquid ejecting apparatus in which the plurality of nozzles N are distributed over the entire width of the medium PP.

2-10. Tenth Modification Example

In the above-described first embodiment, the circulation mechanism 15 includes one sub tank 151, but the present disclosure is not limited to this aspect. Instead of the sub tank 151, the circulation mechanism 15 of the liquid ejecting apparatus 100 may include a supply-side tank coupled to the supply flow path SF1 and storing the ink to be supplied to the liquid ejecting head 50, a recovery-side tank coupled to the recovery flow path SC1 and storing the ink recovered from the liquid ejecting head 50, a pressurization section that pressurizes the inside of the supply-side tank, a decompression section that decompresses the inside of the recovery-side tank, a relay flow path that causes the supply-side tank to communicate with the recovery-side tank, and a relay pump provided in an intermediate portion of the relay flow path and moving the ink from the recovery-side tank to the supply-side tank via the relay flow path. For example, the pressurization section is a compressor. For example, the decompression section is a vacuum pump. In the circulation mechanism 15 configured in this way, the supply-side tank is set to the positive pressure by driving the pressurization section, the recovery-side tank is set to the negative pressure by driving the decompression section, and the relay pump is driven. In this manner, the circulation operation can be performed to circulate the ink in order of the supply-side tank, the supply flow path SF1, the head chip 54, the recovery flow path SC1, the recovery-side tank, the relay flow path, and the supply-side tank. In addition, in this configuration, the pressurization discharge operation may be performed in such a manner that the supply flow path SF1 is pressurized by the pressurization section instead of the pump 159. In the present modification example, the supply-side tank and the recovery-side tank are examples of a "liquid storage section".

2-11. Other Modification Examples

The liquid ejecting apparatus described above can be adopted in various equipment such as a facsimile machine and a copier, in addition to a device dedicated to printing. However, an application of the liquid ejecting apparatus of the embodiments of the present disclosure is not limited to the printing. For example, the liquid ejecting apparatus for ejecting a solution of a coloring material is used as a

29

manufacturing apparatus for forming a color filter of a liquid crystal display device. In addition, a liquid ejecting apparatus that ejects a solution of a conductive material is used as a manufacturing apparatus forming wiring and electrodes of a wiring substrate.

3. Additional Notes

For example, the following configurations can be understood from the forms described above as examples.

According to Aspect 1 as a preferred aspect, there is provided a liquid ejecting apparatus including a plurality of nozzles that eject a liquid in an ejection direction, a common liquid chamber that communicates with the plurality of nozzles and extends in a first direction orthogonal to the ejection direction, a filter that partitions the common liquid chamber into an upstream chamber and a downstream chamber, an inlet for introducing the liquid into the upstream chamber, an outlet for causing the liquid to flow out from the upstream chamber, a liquid storage section configured to store the liquid, a supply flow path that causes the inlet to communicate with the liquid storage section, and a recovery flow path that causes the outlet to communicate with the liquid storage section. A beam portion that couples a pair of inner walls for defining the downstream chamber is provided inside the downstream chamber. The pair of inner walls are separated in a direction intersecting with the first direction when viewed in the ejection direction. A pressurization discharge operation for discharging the liquid from the plurality of nozzles by pressurizing the supply flow path and a circulation operation for circulating the liquid in a circulation path including the liquid storage section, the supply flow path, the common liquid chamber, and the recovery flow path, in order of the liquid storage section, the supply flow path, the common liquid chamber, the recovery flow path, and the liquid storage section are performed. In a filling process of filling the circulation path with the liquid, the circulation operation is performed after the pressurization discharge operation is performed.

The liquid ejecting apparatus according to Aspect 1 performs the circulation operation after discharging the air bubbles inside the downstream chamber. In this manner, compared to an aspect of performing the pressurization discharge operation after the circulation operation is performed, it is possible to prevent the air bubbles from staying in the region pinched between the beam portion and the filter due to the circulation operation, and it is possible to reduce a possibility that the air bubbles may remain in the downstream chamber after the circulation operation.

In Aspect 2 as a specific example of Aspect 1, an on-off valve capable of opening and closing the recovery flow path may be further provided. The pressurization discharge operation may be performed in a state where the recovery flow path is closed by the on-off valve, and the circulation operation may be performed in a state where the recovery flow path is opened by the on-off valve.

In Aspect 3 as a specific example of Aspect 1, in the pressurization discharge operation, the supply flow path and the recovery flow path may be pressurized to generate a first flow in which the liquid flows in order of the supply flow path, the common liquid chamber, and the plurality of nozzles, and a second flow in which the liquid flows in order of a portion or all of the recovery flow path, the common liquid chamber, and the plurality of nozzles.

In the liquid ejecting apparatus according to Aspect 3, as in the liquid ejecting apparatus according to Aspect 1, compared to an aspect in which the air bubbles inside the

30

common liquid chamber are discharged only through the first flow in the pressurization discharge operation, it is possible to reduce the amount of the air bubbles remaining inside the common liquid chamber.

5 In Aspect 4 as a specific example of Aspect 1, a flow path forming member that defines a portion of the downstream chamber and supports the filter may be provided. The beam portion may be a portion of the flow path forming member, and a portion of the filter may be supported by the beam portion.

10 The liquid ejecting apparatus according to Aspect 4 can stably support the filter by preventing bending of the filter, and can prevent the air bubbles from staying in the downstream chamber by performing the pressurization discharge 15 operation before the circulation operation.

In Aspect 5 as a specific example of Aspect 1, the filter and the beam portion may be disposed with a gap in the ejection direction, and a dimension of the gap in the ejection direction may be shorter than a distance between the beam 20 portion and a bottom surface of the downstream chamber.

The liquid ejecting apparatus according to Aspect 5 can stably support the filter by preventing bending of the filter, and can prevent the air bubbles from staying in the downstream chamber by performing the pressurization discharge 25 operation before the circulation operation.

In Aspect 6 as a specific example of Aspect 5, the dimension of the gap in the ejection direction may be shorter than the dimension of the beam portion in a second direction orthogonal to both the ejection direction and the first direction.

30 In the liquid ejecting apparatus according to Aspect 6, compared to an aspect in which the dimension of the gap in the ejection direction is longer than the dimension of the beam portion in the second direction, while a decrease in rigidity of the flow path forming member is prevented, the pressurization discharge operation is performed before the circulation operation. In this manner, it is possible to prevent the air bubbles from staying in the downstream chamber.

In Aspect 7 as a specific example of Aspect 5, the dimension of the gap in the ejection direction may be shorter than a dimension of the beam portion in the ejection direction and a dimension of the beam portion in the first direction.

40 In the liquid ejecting apparatus according to Aspect 7, compared to an aspect in which the dimension of the gap in the ejection direction is longer than a dimension of the beam portion in the second direction, and an aspect in which the dimension of the beam portion in the ejection direction is longer than the dimension of the beam portion in the first direction, while a decrease in rigidity of the flow path forming member is prevented, the pressurization discharge operation is performed before the circulation operation. In this manner, it is possible to prevent the air bubbles from staying in the downstream chamber.

45 In Aspect 8 as a specific example of Aspect 1, the beam portion may be disposed between the inlet and the outlet when viewed in the ejection direction.

50 According to Aspect 9 as a preferred aspect, there is provided a filling method for a liquid ejecting apparatus including a plurality of nozzles that eject a liquid in an ejection direction, a common liquid chamber that communicates with the plurality of nozzles and extends in a first direction orthogonal to the ejection direction, a filter that partitions the common liquid chamber into an upstream chamber and a downstream chamber, an inlet for introducing the liquid into the upstream chamber, an outlet for causing the liquid to flow out from the upstream chamber, a liquid

31

storage section configured to store the liquid, a supply flow path that causes the inlet to communicate with the liquid storage section, and a recovery flow path that causes the outlet to communicate with the liquid storage section. A beam portion that couples a pair of inner walls for defining the downstream chamber is provided inside the downstream chamber, the pair of inner walls are separated in a direction intersecting with the first direction when viewed in the ejection direction, a pressurization discharge operation for discharging the liquid from the plurality of nozzles by 10 pressurizing the supply flow path and a circulation operation for circulating the liquid in a circulation path including the liquid storage section, the supply flow path, the common liquid chamber, and the recovery flow path, in order of the liquid storage section, the supply flow path, the common liquid chamber, the recovery flow path, and the liquid storage section are performed. The filling method includes performing a filling process of filling the circulation path with the liquid, in which the circulation operation is performed after the pressurization discharge operation is performed. 15

According to Aspect 9, the same advantageous effect as that of Aspect 1 can be obtained.

In Aspect 10 as a specific example of Aspect 9, an on-off valve configured to open and close the recovery flow path 25 may be further provided. The pressurization discharge operation may be performed in a state where the recovery flow path is closed by the on-off valve. The circulation operation may be performed in a state where the recovery flow path is opened by the on-off valve. 30

In Aspect 11 as a specific example of Aspect 9, in the pressurization discharge operation, the supply flow path and the recovery flow path may be pressurized to generate a first flow in which the liquid flows in order of the supply flow path, the common liquid chamber, and the plurality of nozzles, and a second flow in which the liquid flows in order of a portion or all of the recovery flow path, the common liquid chamber, and the plurality of nozzles. 35

According to Aspect 11, the same advantageous effect as that of Aspect 3 can be obtained.

In Aspect 12 as a specific example of Aspect 9, a flow path forming member that defines a portion of the downstream chamber and supports the filter may be further provided, the beam portion may be a portion of the flow path forming member, and a portion of the filter is supported by the beam portion. 45

According to Aspect 12, the same advantageous effect as that of Aspect 4 can be obtained.

In Aspect 13 as a specific example of Aspect 9, the filter and the beam portion may be disposed with a gap in the ejection direction, and a dimension of the gap in the ejection direction may be shorter than a distance between the beam portion and a bottom surface of the downstream chamber. 50

According to Aspect 13, the same advantageous effect as that of Aspect 5 can be obtained.

In Aspect 14 as a specific example of Aspect 13, the dimension of the gap in the ejection direction may be shorter than a dimension of the beam portion in a second direction orthogonal to both the ejection direction and the first direction. 55

According to Aspect 14, the same advantageous effect as that of Aspect 6 can be obtained.

In Aspect 15 as a specific example of Aspect 13, the dimension of the gap in the ejection direction may be shorter than a dimension of the beam portion in the ejection direction and a dimension of the beam portion in the first direction. 60

32

According to Aspect 15, the same advantageous effect as that of Aspect 7 can be obtained.

In Aspect 16 as a specific example of Aspect 9, the beam portion may be disposed between the inlet and the outlet when viewed in the ejection direction. 5

What is claimed is:

1. A liquid ejecting apparatus comprising:
nozzles configured to eject a liquid in an ejection direction;

a common liquid chamber that communicates with the nozzles and extends in a first direction orthogonal to the ejection direction;

a filter that partitions the common liquid chamber into an upstream chamber and a downstream chamber;
an inlet for introducing the liquid into the upstream chamber;

an outlet for causing the liquid to flow out from the upstream chamber;

a liquid storage section configured to store the liquid;
a supply flow path that causes the inlet to communicate with the liquid storage section; and

a recovery flow path that causes the outlet to communicate with the liquid storage section, wherein

a beam portion that couples a pair of inner walls for defining the downstream chamber is provided inside the downstream chamber,

the pair of inner walls are separated in a direction intersecting with the first direction when viewed in the ejection direction,

a pressurization discharge operation for discharging the liquid from the nozzles by pressurizing the supply flow path and a circulation operation for circulating the liquid in a circulation path including the liquid storage section, the supply flow path, the common liquid chamber, and the recovery flow path, in order of the liquid storage section, the supply flow path, the common liquid chamber, the recovery flow path, and the liquid storage section are performed, and

in a filling process of filling the circulation path with the liquid, the circulation operation is performed after the pressurization discharge operation is performed.

2. The liquid ejecting apparatus according to claim 1, further comprising:

an on-off valve configured to open and close the recovery flow path, wherein

the pressurization discharge operation is performed in a state where the recovery flow path is closed by the on-off valve, and

the circulation operation is performed in a state where the recovery flow path is opened by the on-off valve.

3. The liquid ejecting apparatus according to claim 1, wherein

in the pressurization discharge operation, the supply flow path and the recovery flow path are pressurized to generate a first flow in which the liquid flows in order of the supply flow path, the common liquid chamber, and the nozzles, and a second flow in which the liquid flows in order of a portion or all of the recovery flow path, the common liquid chamber, and the nozzles.

4. The liquid ejecting apparatus according to claim 1, further comprising:

a flow path forming member that defines a portion of the downstream chamber and supports the filter, wherein the beam portion is a portion of the flow path forming member, and

a portion of the filter is supported by the beam portion.

33

5. The liquid ejecting apparatus according to claim 1, wherein the filter and the beam portion are disposed with a gap in the ejection direction, and a dimension of the gap in the ejection direction is shorter than a distance between the beam portion and a bottom surface of the downstream chamber. 5
6. The liquid ejecting apparatus according to claim 5, wherein the dimension of the gap in the ejection direction is 10 shorter than a dimension of the beam portion in a second direction orthogonal to both the ejection direction and the first direction. 10
7. The liquid ejecting apparatus according to claim 5, wherein the dimension of the gap in the ejection direction is 15 shorter than a dimension of the beam portion in the ejection direction and a dimension of the beam portion in the first direction. 15
8. The liquid ejecting apparatus according to claim 1, wherein the beam portion is disposed between the inlet and the outlet when viewed in the ejection direction. 20
9. A filling method for a liquid ejecting apparatus including nozzles that eject a liquid in an ejection direction, a common liquid chamber that communicates with the nozzles and extends in a first direction orthogonal to the ejection direction, a filter that partitions the common liquid chamber into an upstream chamber and a downstream chamber, an inlet for introducing the liquid into the upstream chamber, an outlet for causing the liquid to flow out from the upstream chamber, a liquid storage section configured to store the liquid, a supply flow path that causes the inlet to communicate with the liquid storage section, and a recovery flow path that causes the outlet to communicate with the liquid storage section, wherein 25
- 30 a beam portion that couples a pair of inner walls for defining the downstream chamber is provided inside the downstream chamber, 35
- 30 the pair of inner walls are separated in a direction intersecting with the first direction when viewed in the ejection direction, 40
- 40 a pressurization discharge operation for discharging the liquid from the nozzles by pressurizing the supply flow path and a circulation operation for circulating the liquid in a circulation path including the liquid storage section, the supply flow path, the common liquid chamber, and the recovery flow path, in order of the liquid storage section, the supply flow path, the common 45

34

- liquid chamber, the recovery flow path, and the liquid storage section are performed, and the filling method comprises performing a filling process of filling the circulation path with the liquid, in which the circulation operation is performed after the pressurization discharge operation is performed. 5
10. The filling method according to claim 9, wherein an on-off valve configured to open and close the recovery flow path is further provided, the pressurization discharge operation is performed in a state where the recovery flow path is closed by the on-off valve, and the circulation operation is performed in a state where the recovery flow path is opened by the on-off valve. 10
11. The filling method according to claim 9, wherein in the pressurization discharge operation, the supply flow path and the recovery flow path are pressurized to generate a first flow in which the liquid flows in order of the supply flow path, the common liquid chamber, and the nozzles, and a second flow in which the liquid flows in order of a portion or all of the recovery flow path, the common liquid chamber, and the nozzles. 15
12. The filling method according to claim 9, wherein a flow path forming member that defines a portion of the downstream chamber and supports the filter is further provided, the beam portion is a portion of the flow path forming member, and a portion of the filter is supported by the beam portion. 20
13. The filling method according to claim 9, wherein the filter and the beam portion are disposed with a gap in the ejection direction, and a dimension of the gap in the ejection direction is shorter than a distance between the beam portion and a bottom surface of the downstream chamber. 25
14. The filling method according to claim 13, wherein the dimension of the gap in the ejection direction is shorter than a dimension of the beam portion in a second direction orthogonal to both the ejection direction and the first direction. 30
15. The filling method according to claim 13, wherein the dimension of the gap in the ejection direction is shorter than a dimension of the beam portion in the ejection direction and a dimension of the beam portion in the first direction. 35
16. The filling method according to claim 9, wherein the beam portion is disposed between the inlet and the outlet when viewed in the ejection direction. 40

* * * * *
